UNITED STATES PATENT OFFICE

KARL E. PEILER, OF WEST HARTFORD, AND WILLIAM T. BARKER, JR., OF HARTFORD, CONNECTICUT, ASSIGNORS TO HARTFORD-EMPIRE COMPANY, OF HARTFORD, CONNECTICUT, A CORPORATION OF DELAWARE

GLASS FEEDER APPARATUS

Application filed June 3, 1929. Serial No. 367,975.

Our invention relates to the feeding of molten glass in mold charges of controllable weight and shape and severed while in suspension below a discharge outlet of a container for a supply of the molten glass. More specifically described, the invention relates to the feeding of mold charges by the use of automatic feeding apparatus of the type known in the art as the "Hartford single feeder", 10 a disclosure of which may be found in the Hartford-Empire Company's British Patent No. 227,078 of June 11, 1924.

An automatic feeding apparatus of the type above mentioned includes a plunger 15 which is reciprocated in the glass in the container in working alignment with the discharge outlet so that the flow of glass through the outlet is periodically accelerated by the downstroke of the plunger and is periodical- 20 ly retarded, stopped or reversed by the up- stroke of the plunger. The plunger reciprocations are controlled by cam actuated operating mechanism which is provided with adjustments whereby either the lower limit or 25 the upper limit of the plunger strokes may be varied during the operation of the plunger or both the lower and upper limits of such plunger strokes may be varied. A change of the lower limit of the plunger stroke may be 30 employed to change the shape of the suspended mold charges assuming constant frequency of severance of such mold charges, without any appreciable change of weight of such charges while a change of the upper limit only 35 of the plunger strokes will effect a change of weight of the mold charges while maintaining the same general shape thereof. Of course, a change of both upper and lower limits of the plunger strokes will tend to cause 40 a change of both shape and weight.

An automatic glass feeder of the type above referred to has many other adjustments which need not be mentioned herein.

An object of the present invention is to improve an automatic feeding apparatus of the type referred to by providing further adjustments for the plunger operating mechanism whereby more extensive adjustments of either weight or shape or both weight and 50 shape of the charges may be obtained without

interruption of the operating movements of the plunger and without a change of the plunger actuating cam.

A further object of the invention is a provision in a feeding apparatus of the type described of an improved arrangement for adjusting the plunger operating mechanism so as to vary selected individual plunger reciprocations for the formation of mold charges of each of successive series which are repeated in cyclic order so that series of charges, each having a weight and/or shape separately regulable within wide ranges, may be produced in cyclic order.

Other objects and advantages of the invention will be apparent from the following description, when it is considered in conjunction with the accompanying drawings, in which:

Figure 1 is a fragmentary plan view, with portions broken away or omitted and with other portions in horizontal section, showing the plunger operating mechanism and associate parts of an automatic feeder equipped with improvements embodying the present invention;

Fig. 2 is a view generally in elevation but partly in vertical section, showing the plunger operating mechanism and improved adjusting means therefor, according to the present invention;

Fig. 3 is a somewhat diagrammatic plan view of the feeder having improved plunger operating and adjusting means according to the present invention in association with a rotary mold carrying table of a forming machine and with timing mechanism arranged to be actuated by adjustable cams on the mold table to regulably control the operations of the improved mechanism for adjusting the plunger mechanism of the feeder, and

Fig. 4 is a somewhat diagrammatic side elevation of the structure shown in Fig. 3, with one of the cam supporting and adjusting parts on the mold table as shown in vertical section.

Generally described, the invention contemplates the provision of a toggle mechanism in lieu of a rigid generally vertical link of the plunger operating mechanism of the usual

feeder of the type described, together with automatically acting mechanism for adjusting the effective length of the toggle at any selected time in relation to a cycle of reciprocation of the discharge regulating plunger and to any desired extent within a considerable range. A plurality of actuating devices, each operable at an independently adjustable time and in such manner as to effect an independently regulable adjustment of the toggle are included in such toggle adjusting mechanism, whereby different variations of the effective length of the toggle may be produced for different strokes of the plunger and a series of different toggle adjustments and consequently plunger reciprocations of different weight regulating and/or charge shaping effects may be repeated in cyclic order. Series of charges of different weight or shape or weight and shape thus may be obtained in cyclic order and repeated until further adjustments of the time and/or character of the operation or operations of one or more of the actuating devices of the toggle adjusting mechanism or of the charge regulating parts of the feeder have been effected. Timing mechanism is provided for independently controlling the respective adjustments of the toggle for the charges of each of successive series and for co-ordinating such adjustments with the operations of the associate glassware fabricating machine with which the operations of the charge feeding parts of the feeder are co-ordinated.

Referring now to the drawings, we show in Fig. 1 a glass feeding forehearth 1 which may be appurtenant to a melting tank or furnace, not shown. The forehearth has a spout 2 provided with a discharge outlet in its bottom which will be constantly submerged by molten glass from the melting tank or furnace. A plunger 3 of refractory material depends from above into the forehearth 1 and is reciprocable in working alignment with the aforesaid discharge outlet. The plunger 3 is carried by a vertically reciprocable substantially horizontal carrier 4 which may be supported intermediate its length on a bracket 5, Fig. 2, so as to be capable of angular adjustment about an upright post 6 on such bracket. The bracket 5 is provided at its opposite ends with depending guide rods 7 and 8, respectively, which slide through vertically apertured guide portions of the frame structure of the forehearth as the bracket is reciprocated vertically by means which will be presently described. The guide member 8 projects vertically above the bracket 5 and is connected by adjusting and fastening mechanism, generally indicated at 9, with the adjacent end of the plunger carrying arm 4. The specific plunger supporting and operating parts together with adjustments and advantages thereof are fully disclosed in the aforesaid British Patent No. 227,078.

The means for reciprocating the plunger may include a cam 10 mounted on a drive shaft 11 which may be driven from the motor 12, Figs. 3 and 4. A cam roll 13 on an arm 14 that is mounted on a fixed pivot 15 is connected by a rigid link 16 with a horizontal pivot element 17. The pivot element 17 may be adjusted along an arcuate slot 18 in one of the members 19 of a compound lever 20 by means of the adjusting screw 21. The compound lever 20 comprises in addition to the member 19 a member 22, both of said lever members being pivoted in a horizontal pivot element 23. The lever member 22 carries an adjusting screw 24 which bears against an abutment 25 on the adjacent end portion of the lever member 19, whereby the power applying end of the lever member 22 may be raised or lowered independently of movement of the lever member 19. The power applying end of the member 22 of the compound lever, in the type of feeder shown in the British patent above referred to, is connected with the bracket 5 by a substantially vertical rigid link, whereby each rotation of the cam 10 will cause a reciprocation of the plunger 3. In the usual plunger operating mechanism, the slot 18 is struck by a radius about the axis of the cam supporting shaft 11 when the plunger is at the lower end of its stroke so that adjustment of the pivot 17 along the slot 18 will vary the amplitude of the reciprocation of the plunger and therefore the upper limit of such reciprocation without varying the lower limit of the plunger stroke. This adjustment will effect a change of weight of the charges as distinguished from a change of shape. The lower limit of the plunger stroke may be adjusted by turning the screw 24 to adjust the angular relation between the members 19 and 22 of the compound lever 20 and thereby to adjust vertically the position of the entire path of reciprocation of the plunger without changing the amplitude of such reciprocation. A change of the lower limit of the plunger stroke is particularly effective to change the shape of the suspended charges. Consequently, it is apparent that by suitable manipulations of the adjusting mechanism just described, either the shape or weight or both weight and shape of the mold charges may be adjusted within limits.

The feeding apparatus includes a pair of cooperative shear blades 26 mounted on pivoted arms 27, Fig. 1, arranged to be actuated by a cam 28 through the motion transmitting mechanism 29 so that the shear blades will be closed to sever suspended mold charges below the feeder outlet in timed relation to the reciprocations of the plunger and with constant frequency.

With the construction just described, predetermined regulably controlled shape and weight of the charges will be maintained after each adjustment of the plunger operat-

ing mechanism for subsequent reciprocations of the plunger until a further adjustment of such plunger operating mechanism has been made.

5 The present invention contemplates the removal of the aforesaid rigid link between the compound lever 20 and the bracket 5 and the substitution for such link of a toggle comprising the lower toggle member 30 and the upper toggle member 31, Fig. 2. As shown, the lower toggle member 30 is connected with the member 22 of the compound lever 20 by a horizontal pivot element 32 while the upper toggle member 31 is connected with the bracket 5 by a horizontal pivot element 33 and the adjacent ends of the toggle members 30 and 31 are connected by the horizontal pivot element 34. This horizontal pivot element 34 is connected by a link 35 with a block lever 36 which is fulcrumed on the horizontal pivot element 37. The toggle is bent toward the block 36 and a depending projection 38 at the lower end of the upper toggle member 31 is adapted to engage with a portion of the lower toggle member 30 when the toggle members are disposed in a substantially vertical line so as to prevent bending of the toggle past such straight line and in the opposite direction. Swinging movement of the block lever 36 about its supporting pivot 37 will transmit motion through the link 35 to the pivot element between the toggle members 30 and 31 so that the angular relation between such members and therefore the effective length of the 25 toggle link between the compound lever 20 and the bracket 5 will be varied. When the effective length of the toggle link is increased, the position of the path of reciprocation of the plunger will be raised while lessening of the effective length of the toggle will lower the position of the path of reciprocation of the plunger. Should the increase of length of the toggle be effected after the upstroke of the plunger has commenced, it is obvious 40 that only the upper limit of such upstroke will be changed and this will have the effect of increasing the weight of the succeeding mold charge. Should such lengthening of the toggle take place at the beginning or during 45 an early part of the upstroke of the plunger, the characteristics of the upstroke of the plunger may likewise be changed so that a change of shape of the succeeding mold charge will be effected. Should the increase of length 50 of the toggle be effected during a portion of the upstroke which is not effective to retract or retard discharge of glass through the outlet, the change of weight will be effected with a minimum of shape change. Decrease of 55 the effective length of the toggle likewise will cause a change of weight or shape or both weight and shape which may be controlled both as to extent and character by regulation 60 of the extent of the decrease of length of the 65 toggle and the time in the cycle of recipro-

cation of the plunger at which said decrease is initiated. The speeds at which the changes of the length of the toggle are effected with relation to the speeds of the cam actuated reciprocations of the plunger also may have 70 a bearing on the extent and character of the weight or shape or weight and shape variations of the charges. The improved toggle adjusting mechanism therefore comprises means for adjusting both the extent of the 75 increase or decrease of the effective length of the toggle, means for variably timing the beginning of such adjustment of the toggle in a cycle of reciprocation of the plunger or with relation thereto. The invention also 80 contemplates suitable regulation of the speed of adjustment of the toggle.

To these ends, the block 36 may be provided with a plurality of similar bores or sockets 39 which open through the top of such block and constitute slideways for vertically adjustable contact sections 40 of the block lever. Such contact sections have suitable contact portions or elements, shown as rollers 41, at their upper ends. Each of the vertically adjustable sections 40 may be adjusted along its slideway 39 and supported therein by an adjusting screw 42, a stop projection 43 being provided at the lower end of each member 40 for engaging with a stop shoulder 44 at the interior of the slideway to limit the upward movement of the slide member 40 in its slideway. In the particular embodiment of the invention that is illustrated in the drawings, the block lever 36 is provided with 100 three of the members 40. The roller 41 at the upper end of each of such members is in contact with the lower end of a central power applying projection or rod 45 that depends from a piston 46 in a cylinder 47 that is 105 mounted above the corresponding slideway 39 in the block 36. The cylinders 47 may be secured to a suitable bracket or portion of the frame structure of the forehearth, as in the position shown in Fig. 3. An adjustable 110 stop screw 48 on the block lever 36 is adapted to abut a fixed stop, which may be a portion 49 of the supporting structure for the forehearth, whereby the upper limit of the swinging movement of the lever 36 and consequently the maximum extent of bend of the toggle link may be predetermined and regulably controlled. A spring 50 connects the toggle pivot 34 with a stationary part and tends to maintain the block lever 36 at the 115 upper limit of its swinging movement.

Each of the pistons 46 and a portion of its stem 45 may be hollow to provide a pocket for the reception of a compression spring 51 which bears at its upper end against the upper cylinder head and at its lower end against the bottom of the pocket so as to maintain the lower end of the piston rod continuously against the roller 41 at the upper end of the associate slide member 40. The spring 50 120

will tend to maintain the block 36 raised and thus will tend to return the pistons 46 toward the upper ends of their cylinders 47 after such pistons have been forced downwardly, as by means of pressure fluid admitted to the upper end of a cylinder through supply and exhaust pipes 52. The weight of the plunger and its supporting mechanism also will tend during downstrokes of the plunger to return the pistons toward their upper positions until the stop 48 contacts with the member 49. Each cylinder may be provided with an opening 53 adjacent to its lower end to allow the escape of air from below the piston 46 as such piston moves downward and such opening or a pipe 54 secured therein may be provided with suitable means, such as a bleeder valve, whereby the rate of escape of air from below the piston may be regulated to regulate the speed of downward movement of such piston. The pressure supply and exhaust pipes 52 likewise may be provided with bleeder valves, not shown, or suitable means for use in regulating the speed of movement of the pistons 46 in the cylinders 47.

It also is obvious that, if desired, means may be connected with the pipes 54 so that pressure may be positively applied to the spaces below the pistons 46 in the cylinders 47 to aid in raising such pistons in their cylinders at the proper times, although such pressure applying means ordinarily will not be required.

Referring now particularly to Figs. 3 and 4, it will be noted that each of the pipes 52 is connected with an individual valve, the respective valves being indicated at 55, 56 and 57, one of such valves being shown in section in Fig. 3. Each of these valves controls the application and exhaust of pressure fluid to and from one of the pipes 52 leading to the upper end of one of the cylinders 47.

Suitable timing mechanism is provided for regulably controlling the times of actuation of the respective valves according to particular requirements at any given time. The particular valve actuating timing mechanism illustrated in the drawings comprises an individual cam 58 for each of the valves, such cam being carried by a rotary mold carrying table 59 so as to be adjustable around a periphery of such table with relation to a mold 60 on that table. Such adjustability may be secured by disposing the cam 58 on a stem 61 which may be secured in any one of a plurality of openings 62 in arcuate outer portion of a supporting plate 63 that is secured adjustably by the slot and bolt arrangement indicated at 64, to the peripheral portion of the table 59. The table 59 is shown as provided with four molds spaced uniformly about the axis of rotation of the table and each adapted to receive a mold charge from the feeder. The rotation of the table 59 is synchronized with the operations of the

glass charge feeding apparatus and this may be accomplished in any suitable manner. For example, a rotating part of the feeder may trip a valve 65, Fig. 4, for controlling the starting of the associate glassware forming machine, of which the mold table 59 is a part.

The operation of the embodiment of the invention that has just been described may be substantially as follows:

With the use of four molds on the table 59 and three pneumatic toggle adjusting mechanisms, as described, the stop screw 48 is adjusted so that the toggle will be of the requisite length for the production of a mold charge of a given weight, the shape of such charge being predetermined primarily by the adjustment of the other shape controlling parts of the feeder. This charge, for convenience of explanation, may be termed the base weight and shape charge and such charge is of the required weight and shape to fit one of the molds on the table 59. Assuming that each of the remaining molds 60 has a cavity of a different size and/or shape from that of the mold for the base weight charge, appropriate mold charges for such different molds may be obtained by adjusting the respective contact sections 40 of the lever 36 in their respective slideways 39 and/or by timing the actuations of the valves 55, 56 and 57 with respect to the times of beginning of the reciprocations of the glass discharge regulating plunger for producing the respective charges for these molds. The cams 58 and the stems of the respective valves 55, 56 and 57 are arranged at different levels so that each of such cams will contact only with the stem of its associate valve. For example, the cam 58 for the valve 56 is shown in Fig. 3 as actuating the stem of that valve. Each time a cam 58 contacts with the stem of its associate valve, such valve will be opened against spring pressure, as shown in Fig. 3, to permit pressure fluid to enter the upper end of the associate cylinder 47 and to force the piston 46 downward in such cylinder, thereby swinging the block lever 36 downward to an extent that will vary according to the position in its slideway 39 of the contact section 40 with which that particular piston 46 cooperates whereby the length of the toggle link will be increased to a regulable extent and the succeeding or concurrent upstroke of the glass discharge regulating plunger will be altered. As soon as the cam 58 disengages the stem of its valves 55, 56 or 57, pressure is permitted to exhaust from the associate cylinder 47 and as soon as the movement of the plunger and its operating mechanism will permit, the spring 50 will return the block lever 36 and the piston 46 upwardly to an extent which is limited by the adjustable bolt screw 48. The adjustments of the sections 40 in the slideways of the block lever 36 are mainly relied on to

control a change of weight when the production of series of multi-weight charges repeated in cyclic order are desired, such weight control of course being in addition to that 5 provided by adjustment of the pivot 17 along the slot 18 of the plunger operating mechanism as hereinbefore described. Variations in shape or in both weight and shape of the respective multi-weight charges may be controlled by adjustment of the timing of the 10 toggle adjusting strokes of the respective pistons 46 with respect to the times of beginning of the strokes of the glass discharge regulating plunger for the mold charges 15 which are to be varied or by combinations of such timing adjustments with the weight regulating adjustments of the sections 40 of the lever 36. Thus, it is obvious that by the use of various combinations of weight and/or 20 shape regulating adjustments which have been hereinbefore described, mold charges of practically any desired useful weight or shape may be obtained and that all of such adjustments may be used during the continued 25 operation of the feeder so that the progressive effects of such adjustments may be noted. After the adjustments for a series of mold charges of predetermined different weights or shapes or weight and shapes have 30 been made, such series of charges will be automatically obtained in a cyclic order until further adjustments have been effected.

The particular embodiment of the invention illustrated in the drawings and herein 25 described may be modified in many respects and the features of the invention also may be modified to adapt the invention to different uses or different conditions of service, without departing from the spirit and scope 40 of the invention, as set out in the appended claims.

No claim herein is sufficiently broad or generic to read on the specifically different improved mechanism for adjusting or altering 45 the plunger operating mechanism of the automatic glass feeding apparatus of the co-pending application of Clyde Nagle and Chester B. Hoopes, Ser. No. 393,988, filed September 20, 1929, for apparatus for feeding 50 glass charges, owned by the assignee of the present application, as such features of improvement as are common to said Nagle and Hoopes application and the present application are the prior invention of said Nagle 55 and Hoopes and are disclosed and claimed in their aforesaid application.

We claim:

1. In apparatus for feeding molten glass 60 in mold charges, the combination with a movable glass discharge regulating implement of mechanism including a toggle joint for reciprocating said implement to periodically vary the discharge of glass, and a plurality of independently operable devices for

altering said toggle joint to vary different strokes of the implement in cyclic order.

2. In apparatus for feeding molten glass in mold charges, the combination with a reciprocable glass discharge regulating implement, a mechanism for reciprocating said implement, said mechanism including a toggle joint, and a plurality of pneumatically operated devices for altering the toggle joint for different reciprocations of the implement. 70

3. In apparatus for feeding molten glass in mold charges, the combination with a reciprocable discharge regulating implement, of mechanism for reciprocating the implement, said mechanism including a toggle joint, a plurality of devices independently operable to alter the toggle joint to vary different reciprocations of the implement in cyclic order, and means for adjusting said devices to vary independently the extent of the 80 alterations of said different reciprocations of the implement.

4. In apparatus for feeding molten glass in mold charges, the combination with a reciprocable discharge regulating implement, of mechanism for reciprocating the implement, said mechanism including a toggle joint, a plurality of independently operable devices for altering the toggle joint to vary different strokes of the implement in cyclic order, and means for variably timing the 90 respective alterations of said toggle joint by said devices with relation to the corresponding reciprocations of said implement.

5. In apparatus for feeding molten glass in mold charges, the combination with a reciprocable glass discharge regulating implement, of mechanism for reciprocating said implement, said mechanism including a toggle joint, a plurality of independently controllable devices, each operable to alter said toggle joint to a regulable extent, and timing means for controlling the relative times of operation of said toggle altering devices and for co-ordinating such operations with the operations of a machine for fabricating into glassware the charges of glass from said feeding apparatus. 100

6. In apparatus for feeding molten glass in mold charges, the combination with a reciprocable glass discharge regulating implement of cam actuated mechanism for reciprocating the implement in regular cycles, said cam actuated mechanism including a toggle joint, means, in addition to said cam actuated mechanism, for altering the effective length of said toggle joint, and means for timing the operation of said toggle joint altering means with relation to the time of presentation of a mold on an associated glassware fabricating machine at a position to receive a charge of glass from the feeder. 115

7. In apparatus for feeding molten glass in mold charges, the combination with a reciprocable glass discharge regulating imple- 120

130

- ment of cam actuated mechanism for reciprocating the implement in regular cycles, said cam actuated mechanism including a toggle joint, means in addition to said cam actuated mechanism for altering the effective length of said toggle joint, and means for adjusting said toggle joint altering means to vary the extent of alteration of the toggle joint by said means.
10. 8. In apparatus for feeding molten glass in mold charges of regulably controllable shape and weight, of a reciprocable glass discharge implement, operating mechanism for causing successive reciprocations of said implement, said operating mechanism including a toggle joint, a lever connected to alter said toggle joint, and a plurality of independently operable devices for actuating said lever.
15. 9. In apparatus for feeding molten glass in mold charges of regulably controllable shape and weight, of a reciprocable glass discharge implement, operating mechanism for causing successive reciprocations of said implement, said operating mechanism including a toggle joint, a lever connected to alter said toggle joint, a plurality of independently operable devices for actuating said lever, and means for adjusting said devices to independently control the extent of the respective alterations of said toggle joint.
20. 10. In apparatus for feeding molten glass in mold charges of regulably controllable shape and weight, of a reciprocable glass discharge implement, operating mechanism for causing successive reciprocations of said implement, said operating mechanism including a toggle joint, a lever connected to alter said toggle joint, a plurality of independently operable devices for actuating said lever, and means for independently controlling the times of operations of said lever actuating devices.
25. 11. In glass feeding apparatus, the combination with means for discharging molten glass through an outlet in successive suspended masses of controllable shape, said means including an implement reciprocable toward and from the outlet, and shears arranged to close periodically beneath the outlet to sever mold charges from the said suspended masses, of mechanism for reciprocating said implement in timed relation with the operations of said shears, said implement reciprocating means including a toggle joint, and a plurality of separate devices connected with said toggle joint and each operable to alter said toggle joint to a regulable extent, whereby mold charges of a plurality of different weights may be obtained in cyclic order.
30. 12. In glass feeding apparatus, the combination with means for discharging molten glass through an outlet in successive suspended masses of controllable shape, said means including an implement reciprocable toward and from the outlet, and shears arranged to close periodically beneath the outlet to sever mold charges from the said suspended masses, of mechanism for reciprocating said implement in timed relation with the operations of said shears, said implement reciprocating means including a toggle joint, and a plurality of separate devices connected with said toggle joint and each operable to alter said toggle joint to a regulable extent, and means for independently timing the operation of each of said toggle joint altering devices, whereby a plurality of mold charges of different weights and/or shapes may be obtained in cyclic order.
35. 13. In glass feeding apparatus, the combination with a reciprocable discharge regulating implement of mechanism for reciprocating said implement, said mechanism including a toggle joint, a lever fulcrumed adjacent to said toggle joint, a link connecting said lever with said toggle joint, and a plurality of separate pneumatically operated devices, each operable to actuate said lever to alter said toggle joint.
40. 14. In glass feeding apparatus, the combination with a reciprocable discharge regulating implement, of mechanism for reciprocating said implement, said mechanism including a toggle joint, a lever fulcrumed adjacent to said toggle joint, a link connecting said lever with said toggle joint, said lever including a plurality of similar slideways and a separate slide member in each of said slideways, each of said slide members having a contact element at its outer end, means for independently adjusting the respective slide members in their slideways, a plurality of pneumatically operable devices adjacent to said lever, each of said pneumatically operable devices having a reciprocable stem bearing against the contact element of a slide member of said lever, whereby operation of each said pneumatically operated device will swing said lever to an extent regulable according to the position of the associate slide member in its slideway, and means for independently controlling the time of operation of each of said pneumatically operated devices.
45. 15. The combination with apparatus for feeding molten glass in mold charges, said apparatus including a reciprocable glass discharge regulating implement and a mechanism including a toggle joint for reciprocating said implement, of a plurality of pneumatically operated devices for altering the toggle joint for different reciprocations of the implement, valves for controlling the application of operating fluid to said pneumatically operated devices, a rotary table carrying molds successively presented at a station for receiving charges from the feeding apparatus, and cams carried by the table and adjustable thereon for actuating the valves at times related to the times of presentation of

molds on said table at said charge receiving station.

16. Mechanism comprising a toggle joint, a lever fulcrumed adjacent to said toggle joint, a link connecting said lever with said toggle joint, and a plurality of separate pneumatically operated devices, each operable to actuate said lever to alter said toggle joint.

17. Mechanism comprising a toggle joint, a lever fulcrumed adjacent said toggle joint, a link connecting said lever with said toggle joint, said lever including a plurality of similar slide-ways and a separate slide member in each of said slide-ways, each of said slide members having a contact element at its outer end, means for independently adjusting the respective slide members in their slide-ways, a plurality of pneumatically operable devices adjacent to said lever, each of said pneumatically operable devices having a reciprocable stem bearing against the contact element of a slide member of said lever, whereby operation of each of said pneumatically operated devices will swing said lever to an extent regulable according to the position of the associate slide member in its slide-way, and means for independently controlling the time of operation of each of said pneumatically operated devices.

30 Signed at Hartford, Connecticut, this 31st day of May, 1929.

KARL E. PEILER.

WILLIAM T. BARKER, JR.
